UNITED STATES PATENT OFFICE.

WILLIAM CLARK THORNTON, OF JEFFERSON CITY, MISSOURI.

MILK-CAN.

SPECIFICATION forming part of Letters Patent No. 447,923, dated March 10, 1891.

Application filed June 11, 1890. Serial No. 355,022. (No model.)

To all whom it may concern:

Be it known that I, WILLIAM CLARK THORNTON, a citizen of the United States, residing at Jefferson City, in the county of Cole and State 5 of Missouri, have invented certain new and useful Improvements in Milk-Cans; and I do hereby declare that the following is a full, clear, and exact description of the invention, which will enable others skilled in the art to 10 to which it appertains to make and use the same.

My invention relates generally to milk-cans, and particularly to that class thereof known as "creaming-cans."

15 The object of my invention is to provide a can of the character described that will be cheap and simple in construction and one that will hermetically seal the contents when the can is submerged in water, and cool the 20 exterior and interior portion thereof all at one and the same time.

With this object in view my invention consists of a can having a central water tube or channel extending entirely through the same 25 and a cover having depending inner and outer flanges adapted to fit over the inner and outer edges, respectively of the central tube and can-body proper, to hermetically seal the contents of the can when the same is 30 submerged.

My invention consists, further, in certain details of construction and combination of parts such as will be hereinafter described, and pointed out in the claim.

35 In the accompanying drawings, Figure 1 is a central vertical section of my improved can as in use, the central tube being threaded and secured in the threaded collar on the bottom. Fig. 2 is a view similar to Fig. 1, but 40 showing the central tube soldered in the bottom, and also the bracing-rod at the top to hold the central water-tube securely in place.

In carrying out my invention I employ a 45 can A of any suitable dimensions, and in the bottom a of said can is formed an aperture, preferably circular in shape, and within said apertured bottom is secured the water-tube B, said tube extending from the bottom a entirely through the can to a point slightly 50 above the upper edges of the can, as clearly shown. The central tube may be secured in the bottom by threading the same, as shown

at b, or it may be soldered, as shown at b'. When the tube is threaded into the bottom, both bottoms and the intermediate ring being threaded, into which the end of the tube is turned, is sufficient to retain said tube in a vertical position; but when said tube is soldered in the bottom it is preferred to brace the same at its upper end by means of the 55 radial brace-rod c, extending from the top of the tube to the upper edges of the milk-can. A ring G, having arms G', is preferably employed to hold the upper portion of the tube in position. Said ring is slipped over the 60 said upper end of the tube, and the arms G' have bifurcated ends which removably bear on the top edge of the can-body A. By this means of construction and arrangement the parts are strengthened and made readily detachable and removable.

The top C of my improved milk-can consists, as usual, of the top portion c' and the depending flange or rim c²; but at its central portion is formed an aperture d, in which is 75 secured the depending tube or collar D, said collar being so arranged and constructed that when the cover is properly placed upon the can the depending collar D will enter the central tube B, thus securely closing the can and 80 forming a tubular passage or channel entirely through the same. The object of the central tube is to expose the central portions of the milk to the cooling influences of whatever medium may be employed to cool the 85 outer portions thereof.

While my can could be used in the air, it is preferred to place the same in a tank of cool water, the water being of such depth that the water will rise in the central tube when the 90 can is submerged. The water, entering the central tube, quickly cools the central portions of the milk. When the cover C is placed upon the can, the moment the flange c² reaches the water it hermetically seals the can at its 95 outer edges, and the lower edges of the collar D coming in contact with the water in the central tube seals the inner edges in a similar manner.

From the drawings it will be seen that the 100 cover slopes from the center toward the outer edges of the can, and the flange c² and collar D are arranged at acute angles to said cover.

H indicates handles arranged upon the sides

of the can and so placed that the flange c^3 will rest upon the same and support the cover a suitable distance above the can proper. In this way an air-space is formed, whereby the 5 vapors arising from the milk will be condensed on the under side of the cover and conducted down the sloping cover and flange and into the submerging liquid.

I indicates a faucet tapped midway the 10 height of the can, and I' indicates a cream-gage constructed and applied in the usual manner.

To render the can sufficiently heavy to sink, I employ a flat metallic ring K, attached to the 15 bottom, and, if desired, the bottom may be double and the ring secured between the two bottoms. Below said ring and the lower bottom and in the extended sides of the can are formed a series of perforations k to permit the escape of air.

Having thus described my invention, what I claim is—

In a milk-can, the combination, with the can-body, of the double-weighted bottom having a central screw-threaded opening, a central tube having its lower end seated in said screw-threaded opening, a ring removably fitted over the upper portion of said tube and having arms whose outer ends are bifurcated to detachably engage the upper edge of the 25 can-body to thereby hold the tube in position, and a cover provided at its periphery with a downwardly-contracted flange to lie adjacent to the exterior of the can and at its center with a downwardly flaring or expanding 30 collar to fit in said central tube, said parts being arranged substantially as described.

In testimony whereof I affix my signature in presence of two witnesses.

WILLIAM CLARK THORNTON.
